H. W. BROWN

ELECTROMAGNET

Filed Feb. 13, 1926

Fig. 1.

Inventor:

Harold W. Brown,

by Alexander S. Smith,
His Attorney.

UNITED STATES PATENT OFFICE.

HAROLD W. BROWN, OF SCHENECTADY, NEW YORK, ASSIGNOR TO GENERAL ELECTRIC COMPANY, A CORPORATION OF NEW YORK.

ELECTROMAGNET.

Application filed February 13, 1926. Serial No. 88,134.

My invention relates to improvements in electromagnets, and more particularly to improvements in electromagnets for electroresponsive devices, such as protective relays, whereby desired changes in the operation of the device, such as the relation between the currents necessary to attract and release an electromagnetically actuated member and the value of the current necessary to attract the member, are greatly facilitated.

My invention will be better understood from the following description taken in connection with the accompanying drawing, and its scope will be pointed out in the appended claims.

In the accompanying drawing, Fig. 1 illustrates in a sectional view an electromagnet embodying my invention, and Fig. 2 is a view of the armature shown in Fig. 1, looking upward, certain parts being omitted for clearness.

In time element relays, having a time limit device whose operation is initiated and controlled by the movement of an electromagnetically actuated member, such as an armature, in response to a predetermined condition, for example, currents twenty-five per cent in excess of normal, no harm is done if this excess current does not last too long, but, even though it lasts for less than the dangerous period, and returns to normal, unless the armature is released promptly so as to stop the timing, an unnecessary circuit interruption may occur. In the application of electromagnets to relays, it is, therefore, very desirable, not only for adjustment, but also for assembling and testing, to be able readily to control the relation between the currents that will attract and release the armature, and also to control the value of the current necessary to attract the armature.

In accordance with my invention, I provide an electromagnet comprising an energizing winding 3 and relatively fixed and movable cooperating magnetic elements 4 and 5, respectively. The fixed magnetic element 4 is shown as the yoke or body of the magnet, and is provided with an adjustably mounted hollow pole piece 6. The movable magnetic element 5 is shown as the armature. This comprises a plurality of magnetic members 5, 7 and 8, which are adapted for relative movement so as to permit changes in the shape of the armature. The main or body portion 5 of the armature may be of hollow cylindrical form. For increasing the value of the current at which the armature is released, that is to say, increasing the drop-out point, the lower part of the armature portion 5 may be arranged to have a diminishing cross-section so as to increase the reluctance of the magnetic circuit as the armature moves to the attracted position. This may be done by cutting away portions of the armature as indicated in Fig. 2, so that it has somewhat the shape of the frustum of a pyramid, cylindrical portions 9 being left for alining the armature in its movement through the non-magnetic guide ring 10 which is mounted in a non-magnetic bushing 11.

In order to maintain the parts 5, 7 and 8 of the armature in any given position, and yet be able to change the shape of the armature so as to change the operating characteristic of the electromagnet, the parts 5, 7 and 8 are secured together as a unit by means permitting relative movement and comprising an actuating member such as a non-magnetic rod 12 and a joining member such as a hollow member or tube 13, which is preferably non-magnetic. In order to be able to change the amount of current necessary to attract the armature, that is, the pick-up point, there is secured to one end of the tube 13 the magnetic member 7, and the tube passes through the body portion 5 of the armature freely at the upper end, while the lower end is threaded into the base of the portion 5. Consequently, by changing the position of the armature portion 5 relatively to the tube 13, the gap between the portions 5 and 7 can be varied so as to change the reluctance of the circuit. Suitable means, such as a lock nut 14, may be provided to prevent relative movement of the armature 5 and tube 13 when positioned as desired.

The actuating rod 12 may be connected at its upper end, which passes through a guide plate 15, to a contact controlling mechanism, a timing mechanism, or the like. Se-

cured to the rod 12 is the magnetic member 8, whose position relatively to the magnetic member 7 may be varied so as to change the shape of the armature pole piece which cooperates with the pole piece 6. In order to change the relative position of the members 7 and 8, so as to vary the ratio between the currents at which the armature will be attracted and released, the actuating rod 12 10 extends through the magnetic member 7 and the tube 13 into the lower end of which it is threaded. Suitable means, such as a lock nut 16, may be provided to prevent relative movement of the tube 13 and the 15 rod 12, that is to say, the magnetic members 7 and 8, when positioned as desired.

The magnetic members 7 and 8, which from the armature pole piece, may be arranged to slide one within the other, and 20 their shapes may be, as illustrated, in part cylindrical and in part frusto-conical. Consequently, as they are moved relatively to each other, their effective composite shape may be varied considerably from a 25 comparatively blunt-nosed pole piece to one that is relatively pointed or sharp.

The effect of the magnetic member or pole piece tip 8 is to add to the initial attractive force, but when the armature reaches a certain position, the pull, due to the flux, between the tip 8 and the stationary pole piece 6 into which it projects, becomes substantially zero, so that the increased effect of the tip is eliminated. Obviously, the farther 30 the tip 8 projects from the member 7, that is, the sharper the general contour of the armature pole piece, the greater the initial attractive force, but the quicker the effect of the tip becomes substantially zero. By 35 varying the shape of the armature pole piece in this way, the relation between the pick-up and drop-out current values may be readily varied. Moreover, the value of current necessary to pick up the armature may 40 be varied by changing the relative position of the armature 5 and the magnetic member 7 as heretofore described. Since all these changes can be made by merely working on the parts at the lower 45 end of the magnet, it is unnecessary to take the electromagnet apart or disconnect the rod 12 from the mechanism it controls. Facility in controlling the characteristic of the 50 electromagnet for different predetermined operating conditions is assured.

While I have shown and described my invention in considerable detail, I do not desire to be limited to the exact arrangement shown, but seek to cover in the appended claims all those modifications that fall within the true spirit and scope of my invention.

What I claim as new, and desire to secure by Letters Patent of the United States, is:

1. An electromagnet comprising a wind-

ing, a pole piece, an armature, and means carried by the armature for varying the ratio between the currents in said winding at which the armature will be attracted to and released from said pole piece, and comprising a cooperating pole piece having a plurality of magnetic members arranged for relative movement whereby the shape of the pole piece can be varied in accordance with the relative position of the members. 75

2. An electromagnet comprising a winding, a pole piece, an armature and means carried by the armature for varying the ratio between the currents in said winding at which the armature will be attracted to and released from said pole piece, and comprising a cooperating pole piece having a plurality of magnetic members arranged for relative movement whereby the shape of the pole piece can be varied in accordance with the relative position of the members, said cooperating pole piece and said armature being relatively movable whereby the position of one relatively to the other can be 80 changed to vary the value of the current necessary in said winding to attract the armature. 85

3. An electromagnet comprising an energizing winding, a pole piece, an armature comprising a body portion and means for varying the ratio between the currents in said winding at which the armature will be attracted to and released from said pole piece comprising a cooperating pole piece having a plurality of magnetic members arranged for relative movement, whereby the shape of the cooperating pole piece can be varied in accordance with the relative position of the members, and means for varying the position of said cooperating pole piece relatively to the body portion of the armature whereby to vary the value of the current necessary in said winding to attract the armature. 100

4. An electromagnet comprising relatively fixed and movable magnetic elements characterized by the fact that one of said elements is provided with a pole piece comprising a plurality of magnetic members adapted to have their relative positions varied whereby to change the shape of the pole piece. 110

5. An electromagnet comprising an energizing winding and an armature comprising a plurality of magnetic members adapted for relative movement whereby to permit changes in the shape of the armature. 115

6. An electromagnet comprising a winding, a pole piece and an armature, and means for varying the relation between the currents in said winding at which the armature will be attracted to and released from said pole piece comprising a cooperating pole piece having a plurality of magnetic members arranged for relative movement whereby the shape of the cooperating pole piece can be 120 125

varied in accordance with the relative positions of the members.

7. An electromagnet comprising a winding, an armature, and means for varying the relation between the currents in said winding at which the armature will be attracted and released comprising a pole piece having

a plurality of magnetic members arranged for relative movement whereby the shape of the pole piece can be varied in accordance **10** with the relative position of the members.

In witness whereof, I have hereunto set my hand this 12th day of February, 1926.

HAROLD W. BROWN.
